UNITED STATES PATENT OFFICE.

FRED E. BURRALL, OF GREEN BAY, WISCONSIN, ASSIGNOR TO MCINTYRE-BURRALL COMPANY, OF GREEN BAY, WISCONSIN, A CORPORATION OF WISCONSIN.

DESIGN FOR A HARNESS BUCKLE.

Application filed October 8, 1927. Serial No. 23,677. Term of patent 14 years.

To all whom it may concern:

Be it known that I, FRED E. BURRALL, a citizen of the United States, residing at Green Bay, in the county of Brown and State of Wisconsin, have invented a new, original, and ornamental Design for a Harness Buckle, of which the following is a specification, reference being had to the accompanying drawing, forming a part thereof.

In the drawing:

Fig. 1 is a perspective viewed from the top of a harness buckle embodying the design.

Fig. 2 is a perspective viewed from the bottom.

Fig. 3 is a side elevation.

I claim:

The ornamental design for a harness buckle substantially as shown.

Green Bay, Wisconsin, October 4th, 1927.

FRED E. BURRALL.
